Cyrus M. Walker
By *Wm. Brown*,
ATTORNEY

UNITED STATES PATENT OFFICE.

CYRUS M. WALKER, OF KANSAS CITY, MISSOURI.

UNDERWEAR GARMENT.

1,425,726.

Specification of Letters Patent. Patented Aug. 15, 1922.

Application filed August 5, 1921. Serial No. 489,950.

To all whom it may concern:

Be it known that I, CYRUS M. WALKER, a citizen of the United States, residing at Kansas City, in the county of Jackson and 5 State of Missouri, have invented certain new and useful Improvements in Underwear Garments; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to underwear, and more particularly to a garment of the union suit type, wherein the upper and lower members are connected by an elastic band to relieve strain on the garment proper when the 20 body of the wearer is bent, and thereby avoid tearing at the seams. While an elastic band of ordinary construction is usually sufficient to prevent tearing of the garment, it is possible in extreme cases for the band to reach 25 its elastic limit and yield to the strain and pull of the garment, and it is to obviate such a possibility that I have devised the present improvement, consisting of a reinforcing member of elastic material, substantially 30 similar to the waist band, but wherein the wales extend at right angles thereto, so that they will yield to initial expansion of the waist band and hold before the limit of stretch of the waist band is reached, and 35 prevent the damage which might otherwise occur.

In the accompanying drawings, I have illustrated my invention as applied to a union suit, and

40 In the drawings.

Fig. 1 is a perspective view of such a garment, including my improvement.

Fig. 2 is an enlarged, detail, perspective view of the upper and lower members of the 45 garment, with the connecting waist band, illustrating my stretch limiting member.

Fig. 3 is a detail perspective view of the insert before its application to the garment, and

50 Fig. 4 is an enlarged, sectional view of a portion of one of the garment members, a portion of the waist band and a portion of the insert, showing their assembled relations.

55 Referring more in detail to the drawings:

1 designates the upper and 2 the lower garment members, connected by an ordinary elastic band 3, which usually consists of knitted fabric with the wales running longitudinally of the band. 4 designates the insert which may be of the same material as the waist band and consists of a piece of material of greater length than the width of the band so that there is a slack in the insert when the garment is in normal condition. 60 The ends of the insert are stitched to the garment members with the waist band so that the slack occurs between the ends and across the band.

In applying the insert to the garment, the 70 ends to be stitched into the garment are extended to nearly their elastic limit so that when the stretch occurs upon bending of the wearer's body, the expansion is diagonally across the insert rather than directly 75 at right angles to the waist band thereby effecting distribution of the strain over a greater area, and decreasing tendency of the garment to tear at the seams.

It is apparent that the insert may be applied to the shoulder elastic as well as to the waist band; although the stretch of the waist band will relieve the garment if strain is applied at the shoulder, and it is further apparent that the improvement is adapted for 85 use with garments of any ordinary or well known construction.

What I claim and desire to secure by Letters Patent is:

1. In combination with a garment comprising upper and lower members and a connecting waist band, an elastic insert having its wales extending across the waist band and having its end edges secured to the garment at the upper and lower edges of the 95 band and having a fullness between its ends, the end edges of the insert being held secured in a condition of expansion at approximately the elastic limit of said insert.

2. The method of reinforcing garments comprising upper and lower members and an elastic waist band, which consists in providing an elastic insert, the length of which is greater than the width of the band, initially stretching the ends of the elastic insert to approximately their elastic limit, and sewing the ends thus stretched to the garment at the edges of the band.

In testimony whereof I affix my signature.

CYRUS M. WALKER.
